INTERNAL COMBUSTION ENGINE STRUCTURE

Filed Sept. 13, 1927

2 Sheets-Sheet 2

UNITED STATES PATENT OFFICE

OTIS D. TREIBER, OF COLLINGSWOOD, NEW JERSEY, ASSIGNOR TO TREIBER DIESEL ENGINE CORPORATION, OF CAMDEN, NEW JERSEY, A CORPORATION OF NEW JERSEY

INTERNAL-COMBUSTION-ENGINE STRUCTURE

Application filed September 13, 1927. Serial No. 219,256.

It is necessary at times for the purpose of making repairs or for other purposes that Diesel engines shall be disassembled. For instance, it may be desired to disassemble or remove the cylinder head, cylinder, piston and connecting rod from the remaining portions of the structure. Heretofore in the disassembling of these parts it has been necessary to effect removal thereof from the structure by moving the same in a direction axially of the engine cylinder and head. This necessity has required either that the cam shaft or other means for actuating the valves necessary to be actuated in the operation of such engines shall be located laterally of or to one side of and at a relatively great distance from the said valves; or if the said cam shaft or other means shall have been located directly over the said cylinders then, in order 10 to remove or disassemble the latter from the structure it has been necessary first to remove the said cam shaft or other means.

It is desirable that the cam shaft or other means which may be employed for actuating the valves shall be located directly above the cylinder head or heads of Diesel engine structures in order that the valves for controlling the operation of the engine shall be operated or actuated by the direct action of such cam 20 shaft or other means and that it be unnecessary to remove the same in order to disassemble the engine structure.

The general object, therefore, of the invention is to provide means of novel character whereby the location of the valve actuating mechanism for Diesel engine structures directly above the cylinder heads may be rendered feasible and practical.

The invention also has for its object to provide means whereby the essential parts of a Diesel engine may be disassembled by moving the same in directions laterally of the said engine; that is, in directions transversely of the axis of the engine cylinder.

The invention resides in the novel combination and arrangement of parts as herein-after described in detail, particularly pointed out in the claims and as illustrated in the drawings in which I have illustrated one form 50 of mechanical embodiment thereof. The in-

vention, however, may be embodied in other forms of construction than that illustrated and various changes in the construction may be made within the scope of the claims without departing from the said invention or the principle thereof. 55

In order that the invention may be readily understood and its practical advantages fully appreciated, reference should be had to the accompanying drawings wherein:

Fig. 1 is a view in side elevation of a multi-cylinder Diesel engine structure embodying the invention;

Fig. 2 is a view in transverse vertical section taken on the line 2-2 of Fig. 1;

Fig. 3 is a horizontal sectional view taken on the line 3-3 of Fig. 2;

Fig. 4 is a similar view taken on the line 4-4 of Fig. 2; and

Fig. 5 is an enlarged view of a fragmentary portion of the structure taken in the plane in which Fig. 2 is taken, the parts being shown enlarged in order to show the structure more clearly. 70

In the drawings I have shown a crank casting comprising a base 1 and removable side portions 2. The usual crank shaft is indicated at 3, to the crank arms of which the lower ends of connecting rods 4 are connected, the upper ends of which are connected 75 respectively to pistons 5 which reciprocate within the cylinder linings 6 mounted within the water jacket members 7. The intermediate portions of these members are spaced from the linings 6 but the upper and lower end portions thereof contact with the said linings as indicated at 8 and 9 and form therewith water tight joints. The water jacket members 7 are provided respectively at their upper ends with inwardly projecting flange portions which are provided upon their inner upper edges with grooves 13 of right angular shape in cross section as illustrated, within which outwardly extending square edged flanges 14 at the upper ends of the cylinders 6 are fitted. This relationship is best shown in Figs. 2 and 5 of the drawings. The spacing of the intermediate portions of the jacket members 7 from the linings 6 provides water chambers 15. The cylinder heads 16 85

are mounted upon the upper ends of the cylinders and are secured thereto by means of screw bolts 17, the upper ends of which are in engagement with the lower sides of the said heads while the lower ends thereof extend through openings 18 in flanges 19 which extend outwardly and laterally from the upper ends of the jacket members 7. The upper ends of the cylinders and the cylinder heads are clamped together by means of nuts 10 upon the lower ends of the bolts 17. Short tubular sections 20 extend between the chambers 15 and the interiors of the cylinder heads 16. These sections are secured in openings 15 in the inwardly extending flange portions of the members 7 and project upwardly through openings in the bottoms of the cylinder heads 16.

For the purpose of insuring that the joints 20 between the pistons and the cylinder heads shall be water tight, I have provided in the edges of the upper ends of the linings 6 annular grooves 21 into which project annular 25 projections or beads 22 which are provided on the lower sides of the bottoms of the cylinder heads. Packing or washer rings 23 are located in the bottoms of the said grooves 21. Packings 25 are provided about the tubular sections 20 in the planes of the joints 30 between the cylinders and the said cylinder heads. It will be noted that the upper end portions of the tubular sections 20 fit loosely in the openings in the bottoms of the cylinder heads so that they may be readily withdrawn 35 therefrom.

In the construction as illustrated I have shown a four cylinder engine structure in which the cylinders, cylinder heads, etc. are supported upon a frame structure comprising 40 upright tapered columns 30 and 31 of trapezium shape, the lower ends of which rest upon the upper edges of the opposite sides of the base 1. In the construction as illustrated the columns 30 are located between adjoining engine cylinders while the columns 31 are located outside of and in adjoining relation to the two outermost cylinders. It will be understood, however, that the number of engine cylinders and columns 50 may be increased as may be desired.

The opposite adjoining end portions of the cylinder heads 16 rest upon the upper ends of the said columns. The opposite sides of each of the said cylinder heads are provided 55 with laterally and outwardly extending flanges 35. The flanges of adjoining heads are located in side by side parallel relation to each other as shown in Fig. 1 of the drawings and are connected and clamped together 60 by means of nuts and bolts 36. The opposite ends of each cylinder head are provided with semi-circular grooves 37, the two semi-circular grooves of adjoining cylinder heads 65 operating to form a cylindrical opening as shown in Fig. 3 of the drawings. The base

1, the columns 30 and 31 and the cylinder heads 16 are bound and tied together by means of vertical rods 38 which extend upwardly through the said base, through the columns and through the cylindrical openings provided by the semi-circular grooves in the adjoining ends of the cylinder heads. In the construction as illustrated the opposite ends of each of these tying or binding rods 38 are screw-threaded for the reception of 70 nuts 40 which clamp against the bottom of the base 1 and against the upper sides of the cylinder heads.

For cooperating with the outer ends of the two outside cylinder heads I have provided 80 plates 41 provided with grooves (not shown) which cooperate with the grooves in the adjoining ends of the two outermost cylinder heads to provide cylindrical openings 85 through which the outermost tie rods 38 extend.

The cylinder heads 16 are rigidly secured together by means of the flanges 35 and the bolts and nuts 36 so that together they constitute what is in effect a strong rigid beam 90 at the upper part of the structure.

The side portions 2 of the respective units of the structure are secured at their lower ends to the upper edges of the portions of the opposite sides of the base 1, between the 95 vertical columns previously referred to, by means of screws or the like 45. The upper ends of the said side portions are connected to the opposite side edges of a flanged cover 46 provided with a central flanged opening 100 47 through which the cylinder lining 6 extends. The opposite edges of the side portions 2 of each unit are provided with flanges 50 which contact with the adjoining columns and are secured thereto by means of bolts 51. 105 The joints between these side portions and the portions of the structure to which they are connected are water tight so that the lubricating oil within the crank case chamber cannot escape by leakage therethrough.

The cover plate 46 of each unit is provided at its opposite ends with oppositely extending flanges 52 which are located in contact with the sides of the adjoining columns and the said flanges are secured to the said columns 110 by means of removable bolts 54. It may be noted also that the fastening means by which the side portions 2 are secured in place are removable so that the said portions may be removed whenever desired.

It will be seen that by the means as thus far described the component parts of the engine structure are firmly and rigidly bound together.

The cylinder head is provided with the 115 usual valve structures 60 and 61 which as usual are operated or actuated in timed relation to each other as required in the operation of Diesel engine structures. In Fig. 2 I have shown a spray nozzle structure by means 120

of which liquid fuel is adapted to be supplied to the upper end of the engine cylinder which is shown in longitudinal vertical section in that figure. As will be seen by reference to Fig. 2 the cam shaft 65 is located directly over and above the engine cylinders and the said valve structures and that it is provided with cams 66 which are adapted to contact with movable parts of the said valve structures to effect operation thereof. The cam shaft is mounted upon brackets 67 which in turn are mounted upon the cylinder heads 16 as shown. One of the said brackets at one end of the structure is provided with a laterally extending arm 68 having an opening in its outer end within which the upper end of a vertical shaft 69 is journaled. The lower end portion of said shaft is journaled in a bearing 70 upon the outer end of the horizontal arm of a bracket 71 secured to the adjoining column 31. A bevel gear 72 upon one end of the crank shaft 3 is in engagement with a bevel gear 73 upon the lower end of the vertical shaft 69. Rotation of the bevel gear 72 causes rotation of the bevel gear 73 and the shaft 69 upon which it is mounted. The upper end of the shaft 69 is provided with a bevel gear 75 which engages a bevel gear 76 upon the adjoining end of the cam shaft 65 so that the latter is driven from the crank shaft 3.

Assuming now that it is desired to disassemble the structure in order to repair portions thereof or to effect renewals, such disassembling may be effected by removing one of the side portions 2, which removal may be effected after the removal of the fastening means by which it is secured to the base 1, the columns, and the cover 46; also by removing the fastening means by which the said cover is secured to adjoining columns and to the upper edge of the side portion 2 which is not to be removed; by removing the nuts from the bolts 17 by which the cylinder is connected with the associated cylinder head; by removing the fastening means by which the flanges 35 of said cylinder head are secured to the corresponding flanges of an adjoining cylinder head; and finally by removing the nuts from the upper and lower ends of such of the tie rods 38 as may be found to be necessary. Such fastening means having been removed and the cylinder comprising the jacket member and lining 6 moved downwardly or axially a sufficient distance from the associated cylinder head 16 to withdraw the upper end portions of the tubular sections 20 from the openings through the bottom of the said cylinder head and to disengage the flange 19 from the bolts 17, the parts then may be moved laterally as indicated by the dash and dot position thereof as indicated at 80. The connecting rod 4 may be disconnected from the crank arms of the crank shaft 3 whereupon the cylinder

piston and connecting rod may be shifted in a substantially horizontal lateral direction. It is obvious that the cylinder head may also be moved laterally from underneath the cam shaft 65 and the cams carried thereby.

It will be seen that by thus providing means whereby these parts which have been mentioned may be moved laterally, a structure may be provided in which the cam shaft is located over and directly above the engine cylinders and cylinder heads as shown whereby the valve structures may be operated by cams mounted upon the cam shaft without the necessity of employing intermediate mechanical means or devices.

Having thus described my invention, what I claim and desire to secure by Letters Patent is:

1. In an engine structure of the character described, the combination of a plurality of vertical columns mounted in spaced relation to each other, engine cylinders located between said columns, cylinder heads mounted upon the said cylinders and secured thereto; means for detachably fastening the said columns and the said cylinder heads together, and means for permitting movement of the said engine cylinders and cylinder heads independently of each other horizontally and transversely of the length of the engine structure to remove the same from said structure to thereby effect disassembling of the same.

2. In a structure of the character described, the combination of a crank casing comprising a base portion, side portions and a cover portion detachably connected with each other, the latter having a central opening therein, vertical columns located in parallel spaced relation to each other and supported at their lower ends upon the upper edges of the said base portion, an engine cylinder located between said columns and projecting at its inner end through said opening, and a cylinder head detachably secured to the upper end of the said cylinder and to the said columns, the said engine cylinder and the parts cooperatively related thereto being movable laterally to effect disassembling thereof with respect to other parts of the structure upon detaching the said side portions and cover from each other and from the said columns.

3. In a structure of the character described, the combination of a crank casing comprising a base portion, side portions and a cover portion, the said side and cover portions being detachably connected with each other and to adjoining portions of the structure, a plurality of parallel spaced vertical columns supported at their lower ends upon the said base portion, the said side and cover portions being detachably connected with adjoining columns, an engine cylinder located between adjoining columns, a piston and a piston rod cooperating with the said cylinder.

der, a cylinder head, means for detachably connecting said cylinder head to the said cylinder, the said cylinder head being provided with laterally projecting flanges at the 5 opposite ends of their opposite sides, the flanges of adjoining cylinder heads being detachably secured together, and rods extending vertically through the said columns and detachably engaging the said base and the 10 said cylinder heads to bind and clamp the same together.

4. In a structure of the character described, the combination of a crank casing comprising a base portion, a plurality of engine cylinders, a plurality of relatively wide vertical columns located in parallel spaced relation to each other and supported at their lower ends upon the upper side of the said base, one column being located between each 15 pair of adjoining cylinders and columns being located in adjoining relation to the outer sides of the two outermost engine cylinders, and the said crank casing comprising opposite side portions located between adjoining columns and detachably secured thereto and to the said base portion and a cover detachably connected to the upper ends of said side portions and to the opposing sides of adjoining columns, said cover having a central opening therein, and cylinder heads mounted upon the upper ends of the said cylinders and the said columns and being detachably secured thereto.

5. In a structure of the character described, the combination of a crank casing comprising a base portion, a plurality of engine cylinders, a plurality of relatively wide vertical columns located in parallel spaced relation to each other and supported at their 35 lower ends upon the upper side of the said base, one column being located between each pair of adjoining cylinders and columns being located in adjoining relation to the outer sides of the two outermost engine cylinders, and the said crank casing comprising opposite side portions located between adjoining columns and detachably secured thereto and to the said base portion and a cover detachably connected to the upper ends of said side 40 portions and to the opposite sides of adjoining columns, said cover having a central opening therein, cylinder heads mounted upon the upper ends of the said cylinders and the said columns, means for detachably securing said cylinder heads to the said cylinders, and vertical tie rods extending through the said crank casing and the said columns and detachably connected with the said cylinder heads.

6. In a structure of the character described, the combination of a crank casing comprising a base portion, a plurality of engine cylinders, a plurality of relatively wide vertical columns located in parallel spaced 60 relation to each other and supported at their

lower ends upon the upper side of the said base, one column being located between each pair of adjoining cylinders and columns being located in adjoining relation to the outer sides of the two outermost engine cylinders, and the said crank casing comprising opposite side portions located between adjoining columns and detachably secured thereto and to the said base portion and a cover detachably connected to the upper ends of said side portions and to the opposite sides of adjoining columns, said cover having a central opening therein, cylinder heads mounted upon the upper ends of the said cylinders and the said columns, means for detachably securing said cylinder heads to the said cylinders, vertical tie rods extending through the said crank casing, the vertical columns and between adjoining cylinder heads for detachably tying the said several parts together, and means for detachably connecting adjoining cylinder heads to each other.

7. In an internal combustion engine structure the combination of vertical columns mounted in spaced relation to each other, engine cylinders located between said columns, cylinder heads detachably connected to said cylinders, means adapted to engage said cylinders to support the same against lateral displacement, means for detachably securing said cylinders, cylinder heads and columns together and for detachably securing said first-named means to said columns, said securing means being removable whereby said cylinders and cylinder heads may be moved horizontally to remove the same from the engine structure to effect disassembling thereof.

8. In an internal combustion engine structure the combination of a pair of spaced vertical columns an engine cylinder and a cylinder head supported by said columns, means for detachably securing said columns, cylinder and cylinder head together, means normally acting to hold said cylinder against lateral displacement, and means for detachably securing said last mentioned means to said columns, the said cylinder and said second named means being movable horizontally and laterally upon removal of the said securing means to effect disassembling of the engine structure.

In testimony that I claim the foregoing as my invention, I have hereunto set my name this 31st day of August, A. D., 1927.

OTIS D. TREIBER.
